land, a corporation of England

Application March 5, 1947, Serial No. 732,410
In Great Britain August 2, 1946

18 Claims. (Cl. 250—141)

1

This invention relates to improvements in cathode ray tubes. More particularly it relates to improvements in cathode ray tubes of the type employed in television receiver projection systems.

The main object of the invention is to provide a cathode ray tube of such construction that it is convenient to use within or forming part of the envelope of the tube optical elements formed of materials (such, for example, as a synthetic resin) which continually exude gases when the gas pressure in the vicinity thereof is reduced to a low value.

A further object of the invention is to provide a cathode ray tube of such construction that it is possible to use as a portion of the envelope of the tube a very thin glass wall which has a minimum deleterious effect on an optical image projected therethrough.

According to the invention there is provided a cathode ray tube of the kind employed for the projection of optical images, comprising an envelope containing a fluorescent screen and having a wall thereof through which the optical image is arranged to be projected to a viewing screen and wherein the space within the envelope is divided into two portions, one of which has for at least a part of its boundary the inner surface of the said wall and is maintained at a higher gas pressure than the other, which contains the electron gun for the tube.

Again according to the invention there is provided a cathode ray tube of the kind employed for the projection of optical images comprising an envelope containing a fluorescent screen and having a wall thereof, through which the optical image is projected to a viewing screen and wherein in a space within the envelope bounded at least in part by the said wall is partitioned off from the space containing the electron gun, so that the former space can be maintained at a higher gas pressure than is necessary for efficient working in the space containing the electron gun.

According to a feature of the invention, the envelope also contains a concave mirror for projecting the optical image.

According to a further feature of the invention, the wall through which the optical image is projected is formed so as to provide correction for distortion of the optical image.

According to a further feature of the invention, the wall is arranged to correct for spherical aberration and coma in the image.

According to a still further feature of the in-

2

vention, the two portions of the space within the envelope are continuously evacuated.

The invention is particularly applicable to cathode ray tubes of the kind described in a pending British application, No. 18,284/46, where a shell in the form of a portion of a sphere is incorporated to form a wall of the tube envelope, this shell being used to correct at least in part for the spherical aberration and coma in the projected optical image.

The invention will be hereinafter more particularly described with reference to the accompanying drawing, comprising Figs. 1 and 2, which illustrate, purely by way of example, different embodiments of the invention.

Referring now to Fig. 1, a cathode ray tube comprises a glass neck 1 incorporating an electron gun 2, a cylindrical metal member 4, having secured thereto at one end a spherical metal cover 3 having an aperture to which is sealed the neck 1, and sealed at the other end to the edge of a transparent shell 5, which may have the form of a portion of a sphere, as described in the pending British application, No. 18,284/46, and is designed to correct at least in part for the spherical aberration and coma in the optical image which is projected therethrough. The image is obtained from a fluorescent screen supported within the cylinder 4, on a curved support 6, aligned with neck 1, and is projected through the shell 5, by means of a concave spherical mirror 7, also positioned within the cylinder 4, and provided with a central aperture aligned with the neck 1. The mirror 7 and shell 5 have different radii of curvature but are concentric. A thin plane glass partition 8, divides the space within the envelope into two parts 9 and 10, which are both continuously evacuated by means of an exhausting system 11, comprising diffusion and backing pumps. The space 9, is evacuated by the diffusion pump and the backing pump, while the space 10 is evacuated by the backing pump. The mirror 7 is formed of glass and consequently the space 9 can be evacuated so that a hard vacuum is obtained. The shell 5 may be formed of a synthetic resin (for example, the plastic known under the trade name of "Perspex") which continuously exudes gas when the pressure in part 10 is substantially reduced. This will be immaterial as the vacuum in space 10 need only be of the order which can be produced by the backing pump of exhausting system 11 and still will not interfere with the efficiency of the electron bombardment of the fluorescent screen in space 9.

The arrangement illustrated in Fig. 1 can be modified in any of the following ways without exceeding the spirit and scope of the invention.

(1) An aspherical correcting plate can be positioned between the partition 8 and the shell at the center of curvature of the latter and can be used to provide correction for spherical aberration and coma in addition to that provided by the shell 5.

(2) The partition 8, instead of being made of plane glass, can comprise an aspherical plate designed to correct for spherical aberration and coma. In this case the partition will be positioned coincident with the center of curvature of the shell.

(3) A thick, flat synthetic resin sheet can be substituted for the shell 5 and the aspherical correcting plane positioned between this sheet and the partition as in modification (1) above.

(4) A thick, flat synthetic resin sheet can be substituted for the shell 5, and the partition 8 can comprise the aspherical correcting plate as in modification (2) above.

Referring now to Fig. 2, the cathode ray tube comprises an inner envelope in the form of a glass neck 13 (housing the electron gun, 13a) and a very thin glass main body 14, and an outer envelope in the form of a metal cylinder 16, having secured thereto a spherical metal cover 15, with a central aperture forming a gastight joint with the neck 13, and a spherical shell 17, similar to the shell 5 of Fig. 1. The inner and outer envelopes are separately evacuated by means of an exhausting system 18, comprising diffusion and backing pumps. The inner envelope is evacuated by the diffusion pump and the backing pump while the outer envelope is evacuated by the backing pump. The fluorescent screen is formed upon a convex metal support 19, which may be formed on a convex inner surface of the inner envelope or may be mounted within the inner envelope or may be suitably sealed to the glass to form part of the wall of the envelope. The support 19, may be water cooled by means of a water jacket 20. The pipe work extending to the water jacket 20 is not shown.

The optical image from the fluorescent screen is projected through the shell 17, by means of a concave spherical mirror 21, which, unlike the mirror 7 of Fig. 1, can be formed of a synthetic resin, due to the fact that it is not located in the portion of the envelope housing the electron gun where a hard vacuum is essential. The mirror 21 and shell 17 have different radii of curvature, but are positioned so as to have a common center of curvature. The shell 17 will be formed of a transparent synthetic resin. As the body 14 of the inner envelope can be formed of very thin glass owing to the low gas pressure in the outer envelope, the wall of this body will not distort the optical image to too great an extent. The exhausting system 18 continuously evacuates both the inner and outer envelopes, the outer envelope, which includes the mirror 21 and shell 17, both of which are formed of a material which exudes gases being, as hereinbefore mentioned, connected to the backing pump.

Additional correction for spherical aberration and coma can be introduced by positioning an aspherical correcting plate between the fluorescent screen and the shell 17, at the center of curvature of the shell. A thick, flat, synthetic resin sheet can be substituted for sheet 17, when an aspherical correcting plate is used. The construction shown in Fig. 2 has the advantage as 75

compared with the construction shown in Fig. 1 that the space to be evacuated to the lower gas pressure can be considerably smaller and therefore the pumping apparatus can be simplified.

5 The vacuum in the space 9 of Fig. 1 or the inner envelope of Fig. 2 will be of the order of 10^{-6} mm. of mercury and the vacuum in the space 10 of Fig. 1 or the outer envelope of Fig. 2 will be of the order of .1 mm. of mercury.

10 What is claimed is:

1. In a television projector, a first envelope enclosing a fluorescent screen and an electron gun for projecting a beam of electrons thereon, a second envelope surrounding the outside surface of 15 a part of the wall of the first envelope, a transparent plastic window in said second envelope, means for creating a partial vacuum inside the second envelope, means for intercepting and reflecting light from the fluorescent screen to project it through said window portion of the wall of the second envelope.

2. In a television projector as in claim 1, in which the first and second envelopes have a common portion of their walls which is relatively thin 25 and transparent, one side of this wall being on the inside of the first envelope and the other side thereof being on the inside of the second envelope, the wall being strong enough to withstand gas pressure against its side which is inside the second envelope equal to the pressure differential between a hard vacuum and a partial vacuum.

3. In a television projector as in claim 1, in which the first and second envelopes are sealed 35 together and have a common portion of their walls, the common portion being of sufficient strength to withstand atmospheric pressure on its outside when a hard vacuum has been produced within it, and the means for intercepting and reflecting comprises a perforated, curved 40 mirror within the second envelope disposed with its perforation around the first envelope and a concave surface facing through the first envelope the surface of the fluorescent screen upon which the electron beam is projected.

4. In a television projector as in claim 1, in which the first and second envelopes are sealed together and have a common portion of their walls, the common portion being of sufficient 50 strength to withstand atmospheric pressure on its outside when a hard vacuum has been produced within it and the means for intercepting and reflecting comprises a perforated, concave mirror within the second envelope disposed with its perforation around the first envelope and its concave surface facing through the first envelope the surface of the fluorescent screen upon which the electron beam is projected, the fluorescent surface being convex toward the mirror and optically coaxial therewith.

5. In a television projector as in claim 1, in which the first and second envelopes are sealed together and have a common portion of their walls, the common portion being of sufficient 65 strength to withstand atmospheric pressure on its outside when a hard vacuum has been produced within it, and the means for intercepting and reflecting comprises a perforated, curved mirror within the second envelope disposed with its perforation around the first envelope with a concave surface facing through the first envelope the surface of the fluorescent screen upon which the electron beam is projected, the mirror comprising a plastic material.

6. In a television projector as in claim 1, in

which the first and second envelopes are sealed together and have a common portion of their walls, the common portion being of sufficient strength to withstand atmospheric pressure on its outside when a hard vacuum has been produced within it, the means for intercepting and reflecting comprises a perforated, concave mirror within the second envelope disposed with its perforation around the first envelope with a concave surface facing through the first envelope the surface of the fluorescent screen upon which the electron beam is projected, the fluorescent surface is convex toward the mirror and optically coaxial therewith, and the mirror comprises a plastic material.

7. In a television projector as in claim 1, in which the first and second envelopes have a common portion of their walls which is relatively thin and transparent, one side of this wall being on the inside of the first envelope and the other side thereof being on the inside of the second envelope, the wall being strong enough to withstand a positive gas pressure against its side on the inside of the second envelope which is equal to the pressure differential between a hard vacuum and a partial vacuum, the means for intercepting and reflecting comprises a perforated, curved mirror facing the surface of the fluorescent screen upon which the electron beam is projected and reflecting light therefrom through the common wall as well as through the window portion of the wall of the second envelope, and the beam is projected onto the screen through the perforation in the mirror.

8. In a television projector as in claim 1, in which the first and second envelopes have a common portion of their walls which is relatively thin and transparent, one side of this wall being on the inside of the first envelope and the other side thereof being on the inside of the second envelope, the wall being strong enough to withstand a positive gas pressure against its side on the inside of the second envelope equal to the pressure differential between a hard vacuum and a partial vacuum, the means for intercepting and reflecting comprises a perforated, concave mirror facing the surface of the fluorescent screen with which the electron beam is projected and reflecting light therefrom through the common wall as well as through the window portion of the wall of the second envelope, the beam is projected onto the screen through the perforation in the mirror, and the fluorescent surface is convex toward the concave mirror and has a common optical axis therewith.

9. In a television projector as in claim 1, in which the window portion of the second envelope comprises an optical element for correcting spherical aberrations produced by the means for intercepting and reflecting.

10. In a television projector as in claim 1, in which the window portion is of substantially uniform thickness, its inner and outer surfaces are shaped as portions of the surfaces of concentric spheres, and it corrects, at least in part, for aberrations produced by the means for intercepting and reflecting.

11. In a television projector as in claim 1, in which the first and second envelopes have a common portion of their walls which is transparent, one side of this wall being on the inside of the first envelope and the other side thereof being on the inside of the second envelope, the wall being strong enough to withstand positive gas pressure against its side which is inside the second envelope equal to the pressure differential between a hard vacuum and a partial vacuum, the common wall comprising a correcting plate for at least partially correcting aberrations produced by the means for intercepting and reflecting.

5 6
12. In a television projector, a first envelope whose walls include at least one transparent and relatively thin portion, a fluorescent screen in the first envelope, gun means in the first envelope for producing a beam of electrons and projecting it into the screen, means for scanning the screen with the beam, a second envelope surrounding the outside surface of a thin portion of the wall of the first envelope, the second envelope having relatively thick walls comprising a window portion of a transparent plastic material, means for pumping gas from the space inside the second envelope to the space outside of it to form a partial vacuum, means for intercepting and reflecting light from the screen to controllably project it through a window portion of the wall of the second envelope.

13. In a television projector as in claim 12, in which the window portion comprises a correcting plate for correcting at least in part aberrations produced by the means for intercepting and reflecting.

14. In a television projector as in claim 12, in which the window portion is formed to correct, at least in part, aberrations produced by the means for intercepting and reflecting.

15. In a television projector as in claim 12, in which the first and second envelopes are sealed together and have a common portion of their walls which is strong enough to withstand atmospheric pressure on its outside when there is a hard vacuum inside of it, the means for intercepting and reflecting comprises a perforated, spherical mirror which is disposed with its perforation around the first envelope and is concave toward the fluorescent screen, the screen and the mirror are separated by the first envelope, the fluorescent screen is convex toward and optically coaxial with the mirror, and the fluorescent screen is supported on a metal support comprising part of the first envelope.

16. In a television projector as in claim 12, in which the first and second envelopes are sealed together and have a common portion of their walls which is strong enough to withstand atmospheric pressure on its outside when there is a hard vacuum inside of it, the means for intercepting and reflecting comprises a perforated spherical mirror which is disposed with its perforation around the first envelope and is concave toward the fluorescent screen, the screen and the mirror are separated by the first envelope, the fluorescent screen is convex toward and optically coaxial with the mirror, the fluorescent screen is supported on a metal support comprising part of the first envelope, and cooling means are included which are adjacent to the outside surface of the metal screen support for cooling the fluorescent screen.

17. In a television projector as in claim 1, and means for producing a hard vacuum in the first envelope.

18. In a television projector as in claim 12, in which the envelopes are made of metal except for the plastic window in the second envelope.
